TEMPERATURE REGULATOR

Application filed July 28, 1927. Serial No. 209,103.

This invention relates to valve mechanism, and more particularly to thermostatically controlled valve mechanism for regulating the flow of the cooling medium circulating in the cooling system of an internal combustion engine, whereby the operating temperature of the latter is controlled.

It is an object of this invention to provide novel thermostatically controlled valve mechanism of the above type whereby the flow of the cooling medium may be controlled in a plurality of passages in succession.

Another object of this invention is to provide an improved device of the character described embodying an expandible and collapsible corrugated wall having valves operatively associated with the opposite ends thereof.

Another object of this invention is to provide valve mechanism of the above type wherein a main valve and a by-pass valve are adapted to be actuated in succession.

A further object is to provide a thermostatically controlled valve mechanism embodying a main valve and a by-pass valve, wherein the main valve is adapted to be moved to open position and the by-pass valve is adapted to be moved to closed position in succession.

30 A further object is to provide a unitary structure embodying a main valve and a second valve, one of said valves being adapted to be actuated prior to the other valve.

Other objects relate to the provision of 35 thermostatically controlled valve mechanism, embodying main and by-pass valves, which is compact, inexpensive to manufacture, certain in operation, and which may be readily installed in cooling systems without special 40 design of the parts to which it is operatively connected.

The invention is capable of receiving a variety of mechanical expressions, two of which are shown on the accompanying drawings, 45 but it is to be expressly understood that the drawings are for purposes of illustration only and are not to be construed as a definition of the limits of the invention, reference being had to the appended claims for that purpose.

50 Referring to the drawings, wherein like

reference characters are employed for designating like parts in the several views—

Fig. 1 is an axial section of a thermostatically operated valve mechanism embodying the present invention;

55 Fig. 2 is a bottom plan view of the valve mechanism per se; and

Fig. 3 is an axial section of another and preferred embodiment of the present invention.

In the form shown in Fig. 1, the valve mechanism constituting the subject matter of the present invention is mounted on a cylinder head casting 4 which constitutes a part of the water jacket of an internal combustion engine (not shown). An opening 5 is provided in the cylinder head casting, which opening constitutes a portion of the path for the cooling medium as it flows to the radiator (not shown). Centrally located in opening 5 is a by-pass conduit or pipe 6 which extends downwardly through the cylinder jacket to the usual circulating pump of the motor, the upper end of the by-pass being substantially flush with the upper surface of cylinder head casting 4. A suitable fitting 7, 70 which may be secured to said casting as by means of bolts 8 projecting through the flanged portion of said fitting into said casting, constitutes a passageway for conducting the cooling medium from the water jacket to the radiator. Any other suitable construction and arrangement of passages for the cooling medium may be employed, however, as the elements described above constitute no part, per se, of the present invention.

85 Mounted on the cylinder head casting 4, in a position to surround the opening 5, is a combined support and valve seat member 9, which is substantially cup-shaped, and which is provided with a flanged portion 9a that is 90 clamped between the flanged portion 7a of fitting 7 and the upper surface of casting 4 by means of the bolts 8. In the form shown, support 9, which may be made of sheet metal, is provided with a suitable opening 10 substantially concentric with the opening 5, and preferably a plurality of arms 11 extend inwardly from the outer wall of said opening to an annular portion 12 constituting a supporting ring. Arms 11, which are prefer-

ably formed integral with support 9, divide opening 10 into a plurality of segmental openings.

Fixed attached in any suitable manner to ring 12, as by means of soldering or brazing, and extending upwardly from said ring, is a tubular guide 13. Preferably, guide 13 is provided with an enlarged portion forming a shoulder 13a which is adapted to coact with 10 a perforated disk 14 that slidably surrounds said guide and which is fixedly attached at its periphery, as by means of soldering and brazing, to the lower open end of a cup-shaped casing 15 which is concentric with 15 opening 10 and which constitutes a main valve.

Mounted within the casing 15 is a corrugated flexible tubular wall or bellows 16, the lower end of said wall being fixedly attached 20 to an annular member 17 that is secured at its outer periphery to the inner wall of casing 15 adjacent an inwardly extending, annular ridge 18, which may be formed in said casing, as by means of rolling, to facilitate 25 the location and attachment of annular member 17. Formed integrally with or secured to the inner end of the corrugated wall 16 in any suitable manner, is a disk 19 constituting a movable end wall for the bellows 16. 30 Centrally secured to disk 19 or formed integrally therewith, and extending axially through guide 13 and ring 12, is a valve stem 20, which is preferably in the form of a tube, the inner end of said stem being shown as 35 secured to disk 19 in any suitable manner, as by means of riveting and soldering. The outer end of stem 20 extends a suitable distance beyond ring 12 and is preferably exteriorly threaded to receive a by-pass disk valve 40 21 adapted to coact with the by-pass conduit 6, the upper end of the latter forming the valve seat, and also to engage the end of guide 13 or the annular portion 12 to act as a stop therefor. A thermosensitive fluid 45 is introduced into the space 22 provided between the bellows 16 and the inner wall of casing 15, as through the tubular stem 20 after which the end of said stem is closed as by means of cork and solder 23. A coil spring 50 24, which preferably surrounds guide 13, bears at its upper end against the inner face of disk 19 and at its lower end against the inner face of perforated disk 14, and constitutes a resilient abutment. 55 If desired, a guide member 25 may be provided for the upper end of hollow stem 20. In the form shown, the member 25 is secured to the closed end of cup 15 in a position to have sliding engagement with the 60 inner surface of tubular stem 20. Suitable openings 26 are preferably provided in disk 14 to admit the cooling medium to the inner surface of the corrugated wall 16.

The operation of the apparatus is as follows:—

As the temperature of the cooling medium in the water jacket increases, the heat is transferred through the wall of the thermostat to the thermosensitive medium in space 22 and there is a tendency for end wall 19 and the closed end of cup 15 to move relatively. In most cases the cooling medium is circulated by means of a pump and the pressure of the cooling medium acting through openings 26 on the inner surface of end wall 19, together with the tension of spring 24, tends to prevent movement of the end wall downwardly, while the tension of spring 24 also acts to prevent movement of the cup-shaped casing 15 upwardly relatively to end wall 19. But the pressure of the cooling medium on the upper outer surface of said casing is less than the pressure below disk 14, since the cooling medium flows upwardly, as indicated by the arrow. This differential in pressure acts with the pressure developed in space 22 to force casing 15 upwardly, carrying therewith disk 14 and annular member 17, compressing spring 24 and collapsing the bellows 16, because by-pass valve disk 21 is in engagement 70 with annular portion 12 and prevents upward movement of disk 19. The lower edge of casing 15 constitutes a main valve which coacts with the seat formed by the upper surface of support 9, and as said casing moves 75 upwardly, the cooling medium flows through opening 10, past the valve and valve seat, upwardly through fitting 7, and into the radiator. Prior to, and during the opening of the main valve, a portion of the cooling medium 80 is returned to the pump through the by-pass 6, since valve 21 remains open during movement of casing 15.

If the temperature rises to such a point that disk 14 is moved into engagement with shoulder 13a, further upward movement of the casing is prevented and any increase in temperature serves to force end wall 19 downwardly against the tension of spring 24, whereby valve 21 is moved towards or onto the seat formed by the upper end of the by-pass 6 to close the latter and to cause all of the cooling medium to be delivered into the radiator.

If the weight of casing 15, and its associated parts, is greater than the pressure of the cooling medium below disk 14, it will be apparent that a rise in temperature will cause end wall 19 to be forced downwardly against the tension of spring 24 until valve 21 is seated. Any increase in the temperature now causes casing 15 to be forced upwardly.

It will therefore be apparent that the main valve and the by-pass valve 21 act at different times. When starting the cooling medium flows downwardly through by-pass 6, whereby the engine will be brought quickly to its proper operating temperature. Thereafter it normally flows through opening 5 and the by-pass, because under usual operat- 125 115 100 95 90 85 80 75 70 65 60 55 50 45 40 35 30 25 20 15 10 5 0

ing conditions the by-pass valve does not operate, the main valve formed by casing 15 serving to control the temperature of the cooling medium sufficiently. If the temperature of the cooling medium rises sufficiently, the by-pass is closed and all of the circulating medium goes to the radiator.

- In the embodiment of the invention illustrated in Fig. 3, a tubular guide 27 which is secured to ring 12 in a manner similar to that described in connection with guide 13 of Fig. 1, is provided with a flanged portion 27a, the lower surface of which forms a shoulder adapted to coact with disk 14. The upper surface of flanged portion 27a is engaged by the lower end of a coil spring 28, the upper end of said spring having engagement with the lower face of the movable end wall 19 and constituting a resilient abutment therefor.
- 20 In other respects the structure is similar to that described in connection with Figs. 1 and 2.

In this embodiment of the invention any tendency for movable end wall 19 to be forced downwardly by an increase of pressure in space 22 is resisted by spring 28 but the latter is not effective to resist upward movement of casing 15. The latter is therefore forced from its seat, when the temperature of the 30 cooling medium develops a sufficient pressure in space 22, and if the temperature is sufficiently great, said casing moves upwardly until disk 14 engages the shoulder formed by flange 27a. Further expansion of the thermo-sensitive fluid results in end wall 19 being forced downwardly to move valve 21 to its seat.

It will therefore be perceived that there is provided a thermostatically actuated valve 40 mechanism wherein the flow of the cooling medium may be controlled in a plurality of passages in succession. While the device embodies a main valve and a by-pass valve, said valves are operatively associated with the 45 opposite ends of the thermostat so that the structure is a unit and extremely compact.

The device embodies advantages of both the by-pass and the choker types of thermostats, because under normal conditions, the 50 by-pass valve does not operate and the engine is thereby brought more quickly to the desired temperature, since the cooling medium is recirculated through the by-pass. At the same time the by-pass may be closed if the 55 temperature of the cooling medium rises so high as to render such action desirable.

While two embodiments of the invention have been illustrated and described with considerable particularly, it is to be expressly 60 understood that the invention is not restricted thereto, as the same is capable of receiving a variety of mechanical expressions, some of which will now readily suggest themselves to those skilled in the art, while changes may 65 be made in the details of construction, ar-

rangement and proportion of parts without departing from the spirit of the invention. Reference will therefore be had to the appended claims for a definition of the limits of the invention.

What is claimed is:

1. In a thermostatically operated valve mechanism for controlling the flow of cooling medium in the cooling system of an internal combustion engine, a plurality of valves, a thermostat controlled by the temperature of the cooling medium and operatively connected to said valves, and means yieldingly opposing expansion of said thermostat in one direction, until said thermostat has first expanded in the opposite direction.

2. In a thermostatically operated valve mechanism for controlling the flow of cooling medium in the cooling system of an internal combustion engine, a plurality of valves, and a temperature responsive device controlled by the temperature of said cooling medium and operatively connected to said valves for opening one of said valves and closing another of said valves, and a yielding abutment for said temperature responsive device for resisting operation of one of said valves until said temperature responsive device has first operated the other of said valves.

3. Apparatus of the class described comprising a main valve, a by-pass valve, means biasing the main valve toward its closed position and the by-pass valve toward its open position, and temperature responsive means operatively connected to said valves, said biasing means cooperating with said temperature responsive means to prevent closing of said by-pass valve until after said main valve has opened.

4. In combination with the cooling system of an internal combustion engine of the type employing a by-pass and a main passage for the cooling medium, a valve biased to close said main passage, a valve adapted to close said by-pass, said second-named valve being biased to its open position, and means including a flexible corrugated member having its opposite ends connected to said valves for moving said main valve toward open position, and thereafter moving said by-pass valve toward closed position in succession.

5. A device of the class described comprising a cup-shaped casing constituting a valve, a corrugated member mounted in said casing having one end thereof fixedly attached to the said casing, a second valve operatively connected to said corrugated member, and resilient means for resisting movement of said second valve relative to said first valve.

6. A device of the class described comprising a support, a guide carried thereby, a casing constituting a valve normally having engagement with said support, a corrugated member in said casing, resilient means hav-

ing operative engagement with said corrugated member and said guide, a valve stem extending through said guide and having operative connection with said corrugated member, and a valve carried by said stem.

7. In a device of the class described, a support constituting a valve seat, a guide tube carried by said support, a valve having a stem slidably extending through said guide, 10 a bellows operatively connected to said stem, a casing constituting a valve operatively connected to said bellows and normally engaging said support, and resilient means interposed between said guide and said bellows 15 for resisting movement of said valve stem.

8. In a device of the class described, a support, a casing constituting a valve normally in engagement with said support, a flexible corrugated member in said casing, a valve 20 having a stem operatively connected to said corrugated member, a guide for said stem constituting a stop for limiting movement of the casing in one direction, and resilient means interposed between said corrugated 25 member and said guide for resisting movement of said valve stem.

9. In a thermostatically operated valve mechanism, a plurality of valves, a thermostat having its opposite ends connected to 30 said valves, and resilient means opposing the operation of said thermostat in one direction whereby one of said valves is moved to its limit position before the other valve starts to move.

35 10. In a thermostatically operated valve mechanism for controlling the flow of cooling medium in the cooling system of an internal combustion engine, the combination of a valve seat, a thermostat comprising a casing 40 constituting the main valve and adapted to cooperate with said seat, a flexible corrugated wall in said casing and having one end fixedly secured thereto, a by-pass valve operatively connected to the movable end of 45 said flexible wall, and resilient means for resisting movement of said by-pass valve relative to said main valve.

11. In a thermostatically operated valve mechanism for controlling the flow of cooling 50 medium in the cooling system of an internal combustion engine, the combination of a valve seat, a thermostat comprising a casing constituting the main valve adapted to cooperate with said seat, a flexible corrugated 55 wall in said casing and having one end fixedly secured thereto, a guide member carried by said valve seat, a valve stem connected to the movable end of said flexible wall and movable in said guide member, a spring interposed between said guide member and the movable end of said flexible wall to resist movement thereof, and a by-pass valve operatively connected to said valve stem.

60 12. In a thermostatically operated valve mechanism for controlling the flow of cool-

ing medium in the cooling system of an internal combustion engine, a valve seat member, a thermostat comprising a casing adapted to engage said valve seat member and constitute a valve, a flexible corrugated wall having one end secured to said casing, a valve stem connected to the opposite end of said flexible wall, and a valve on said valve stem.

70 13. In a thermostatically operated valve mechanism for controlling the flow of cooling medium in the cooling system of an internal combustion engine, a valve seat member, a thermostat comprising a casing adapted to engage said valve seat member and constitute a valve, a flexible corrugated wall having one end secured to said casing, a valve stem connected to the opposite end of said flexible wall, a valve on said valve stem, and means cooperating with said flexible wall whereby said valves are operated in succession.

75 14. In a thermostatically operated valve mechanism for controlling the flow of cooling medium in the cooling system of an internal combustion engine, a valve seat member, a thermostat comprising a casing adapted to engage said valve seat member and constitute a valve, a flexible corrugated wall having one end secured to said casing, a valve stem connected to the opposite end of said flexible wall, a valve on said valve stem, and means cooperating with said flexible wall whereby said casing is moved from said valve seat member before said valve stem is operated.

80 15. In a thermostatically operated valve mechanism for controlling the flow of cooling medium in the cooling system of an internal combustion engine, a valve seat member, a thermostat comprising a casing adapted to engage said valve seat member and constitute a valve, a flexible corrugated wall having one end secured to said casing, a valve stem connected to the opposite end of said flexible wall, a valve on said valve stem, and a spring cooperating with said flexible wall to resist movement of said valve stem.

85 16. In a thermostatically operated valve mechanism for controlling the flow of cooling medium in the cooling system of an internal combustion engine, a valve seat member, a thermostat comprising a casing adapted to engage said valve seat member and constitute a valve, a flexible corrugated wall having one end secured to said casing, a valve stem connected to the opposite end of said flexible wall, a valve on said valve stem, a stationary guide member for said valve stem, and a spring interposed between said guide member and said flexible wall.

90 17. In combination, a pair of aligned axially movable valves, a pair of seats limiting the movement of the valves in one direction, a pair of stops limiting the movement of the valves in the opposite direction, a heat sensitive element expandable and contractible as a

70

unit throughout its length, said element being connected to said valves and normally drawing them together, and a spring for biasing the movable valves and heat sensitive element in one direction so that the expansion of the heat sensitive element operates the valves in sequence.

18. In a thermostatic control for the cooling medium of internal combustion engines, frame elements having abutments thereon, a thermostat adapted to slide bodily on said frame elements, a valve member connected to each end of the thermostat and actuated thereby, and resilient means normally urging the thermostat against an abutment whereby the thermostat expands first in one direction to actuate one valve member, then in the other direction to actuate the other valve member.

19. In a thermostatic control for the cooling medium of internal combustion engines, frame elements having spaced abutments thereon, a thermostat having bodily movement on said frame elements limited by said abutments, a valve member actuated by each end of the thermostat, and resilient means normally urging the thermostat against an abutment whereby the thermostat expands first in one direction till it engages another abutment, then in the other direction against the action of the resilient means.

20. In combination, a thermosensitive element having a valve member connected to each end thereof, a support for said element providing an abutment and a stop, and a spring pressing said element against said abutment whereby said element expands in one direction only until it engages said stop.

21. In a thermostatically operated valve mechanism for controlling the flow of cooling medium in the cooling system of an internal combustion engine, a thermosensitive element having a valve member connected to each end thereof, a support for said element permitting expansion of said element successively in opposite directions and providing an abutment, and a spring urging said element against said abutment to resist expansion of said element in one direction as long as said element may expand in the other direction.

In testimony whereof I have signed this specification.

JEAN V. GIESLER.
